CLAIM

The ornamental design for a spinner cap, as shown and described.

DESCRIPTION

FIG. 1 is a front perspective view of the spinner cap of the present invention showing my new design;
FIG. 2 is a front side elevational view thereof;
FIG. 3 is a back side elevational view thereof;
FIG. 4 is a side elevational view thereof;
FIG. 5 is another side elevational view thereof;
FIG. 6 is a top plan view thereof;
FIG. 7 is a bottom plan view thereof;
FIG. 8 is a perspective view of the handle of the spinner cap in an extended use position; and,
FIG. 9 is another perspective view of FIG. 8.
